UNITED STATES PATENT OFFICE.

ALGERNON CLEMENT FULLER, OF WOBURN, ENGLAND.

TELEGRAPHY AND APPARATUS THEREFOR.

1,316,540.

Specification of Letters Patent. Patented Sept. 16, 1919.

Application filed September 22, 1917. Serial No. 192,806.

To all whom it may concern:

Be it known that I, ALGERNON CLEMENT FULLER, a subject of the King of Great Britain and Ireland, and residing at Signal Service Training Centre, Woburn, in the county of Bedford, England, have invented certain new and useful Improvements in Telegraphy and Apparatus Therefor, of which the following is a specification.

10 This invention relates to telegraphy and more particularly to telegraph systems in which the signal currents are broken up into high frequency impulses so that the signals may be audibly received in a telephone receiver.

15 The principal object of the invention is to devise means whereby the telegraph signals cannot be read or overheard by inserting a receiver in the line or in any external circuit designed for the purpose, unless the form of receiving apparatus made in accordance with the present invention is employed.

20 A further object of the invention is to enable telegraphic signals and telephonic speech to be simultaneously carried over the same line, the signals and speech being entirely separate and distinct one from the other.

25 With the above objects in view the invention consists in a telegraph system so arranged that two distinct paths or circuits are provided for the signal and voice currents, and in the provision of means for preventing the high frequency impulses from producing any appreciable inductive effect in the line.

30 In order that the invention may be readily understood, reference is had to the accompanying drawing, the single figure of which is a diagram of the electrical circuits and apparatus employed at each end of the line. Such apparatus comprises both sending and receiving devices for the telegraphic signals and also a telephone set for carrying on conversation, and as the equipment at every station is the same, a description of the one station illustrated in the figure will suffice for all.

35 Referring to the drawing in detail, I have illustrated the apparatus as arranged for connection to a line conductor at *a* and connected to earth at *b*, although of course a complete metallic circuit can be employed if preferred.

r and *t* designate the receiver and trans-

mitter respectively of the telephone set adapted for use in the ordinary way while *l* designates the usual telephone transformer comprising a primary winding *m* connected by a conductor 26 with one of the terminals *p* of the transmitter *t*, and a secondary winding *k* connected by conductor 2 with one of the terminals *o* of the receiver *r*. The other terminal of the receiver is connected by a conductor 1 with the line binding post *a* while the other terminal of the transmitter is connected to earth.

c designates the usual telegraphic sending key and this is connected by means of a conductor 3 through the secondary *k* and wire 2 to line, through the receiver *r*, a choke coil *d* of high impedance being included in this connection by means of a conductor 4. From the back contact *g* of the key *c* extends a conductor 5 to the pivot point 6 of an interrupter. This interrupter comprises a pivoted armature *h* carrying contact springs 7 at its ends. One of said contact springs is adapted to engage a pair of independent contacts 8 and 14, while the other contact spring is arranged to engage a similar pair of contacts 8' and 14'. The contacts 8 and 8' are connected together by a wire 9 and thence by a conductor 10 to a telephonic receiver *i*, shown as of the head type. From the other side of this receiver extends a conductor 11 which connects with a common return wire 12. This extends through apparatus presently to be described to the ground wire *z*. A condenser *f* is connected between the wires 5 and 12 by means of a conductor 30 so as to bridge the contacts 8 of the interrupter, such condenser being in parallel with the receiver *i*.

40 The interrupter above mentioned may be of any suitable type, either mechanical or electrical, its object being to break up the incoming telegraph signals into high frequency impulses so that they may be audible in the telephone receiver *i*. As shown, however, the interrupter is electrical and comprises a polarized armature *h* and a bipolar actuating magnet *h'*. This magnet has two pole pieces *h*² and *h*³ and each of these pole pieces preferably carries a pair of independent windings 16 and 19, such windings having opposite magnetizing effects. A local battery *y* is provided for energizing the interrupter magnet and the energization of such magnet takes place

- over a local circuit comprising conductors 21 and 22, switch *s* and contact 23.
- Sending is done by means of an ordinary direct current battery which is indicated at 5 *x* and when the sending key *c* is depressed, current flows from such battery over the wire 33, wire 27, contact 28, key *c*, wire 4, impedance coil *d*, wire 3, secondary *k* of the transformer, wire 2, receiver *r*, wire 1, 10 and binding post *a* to line, the other side of the battery *x* being connected to ground over the wires 34 and *z*. The intermittent direct current forming the dots and dashes of the ordinary Morse code is not of sufficient 15 frequency to be interfered with by the impedance coil *d*. In other words, this sending current is substantially a direct current and therefore can readily pass through the impedance coil.
- 20 With the above description it is thought that a full understanding of the invention will be had from an explanation of the operation of the system.
- 25 Telegraph signals, comprising intermittent direct current sent out from a sending station over the line, as above described, come in at *a* and flow over the wire 1 through receiver *r*, wire 2, secondary *k* of the transformer *l*, wire 3, impedance coil *d*, 30 wire 4, key *c* and back contact *g*, wire 5 to interrupter armature *h*, from whence the current passes, with the armature in the position shown in the drawings to contact 8' and thence over wires 9 and 10 through receiver *i*, whence it passes over wires 11 and 35 12 to ground. Meanwhile, the switch *s* having been thrown over onto contact 23 for receiving, the interrupter device *h*' is energized from the battery *y* over an independent 40 local circuit. Beginning from one side of battery *y* this circuit includes wire 17, windings 16, wire 15 and contact 14, or wire 20, windings 19, wire 18 and contact 14', (according to the position of the armature 45 *h*) and thence from such armature over the wire 22, contact 23, switch *s*, wire 21, back to battery. Thus the armature *h* is caused to vibrate continuously at a comparatively high rate, thus breaking up telegraph signals 50 coming in over the contacts 8 and 8' into a series of high frequency impulses, so that such signals become readily audible in the telephone receiver *i*. As long as the sending key at the distant station is depressed, current flows continuously through the line and through the choke coil *d*, thus keeping the condenser *f* charged, and at each oscillation of the armature *h* such condenser 55 discharges through the telephone receiver *i*.
- 60 It will be particularly noted, however, that owing to the high impedance of the coil *d*, it is practically impossible for the impulses generated by the interrupter *h* to pass back into the line, since these impulses are 65 of such frequency as to be effectually choked

back by the coil *d*. Therefore while these high frequency impulses are employed in order to affect the telephone receiver, the current in the line is practically a direct current and hence does not produce any inductive effects. In other words, the high frequency impulses for actuating the telephone receiver are confined by the coil *d* to the local receiving apparatus.

70 Telephonic conversation may be carried on between any two stations equipped with my improved apparatus by means of the transmitter *t* and receiver *r* in the usual way. The alternating voice currents coming in over the line pass through the receiver *r*, and 75 secondary *k* of the transformer, but are unable to traverse the impedance coil *d*. They therefore pass to the ground wire *z* over wires 31 and 32 in which is interposed a condenser *e*. This condenser serves to prevent 80 the passage of the telegraph signal currents over the path just traced. The use of such condenser therefore, in combination with the impedance coil *d* enables the direct telegraphic currents and the alternating voice 85 currents to be transmitted simultaneously over the line and to be separated at the receiving station and caused to traverse separate paths. Thus telegraph messages and 90 telephonic conversation can take place simultaneously and independently. The transmitter *t* is connected by means of wires 26 and *z* in a local circuit including the battery *x* and the primary *m* of the transformer *l*, 95 whereby voice currents are induced in the 100 secondary *k* of such transformer in the usual manner.

105 In order to conveniently call a distant station, I provide means for impressing a strong buzzing current on the line so as to produce a loud humming in the receiver *r* at the called station. To this end a contact 24 is arranged to be engaged by the switch *s* and is connected by a wire 25 with the wire 26. Another wire 35 connects the wire 22 110 with the wire 34 below the battery *x*, a push button *g* being interposed in the wire 35. When it is desired to call a station and the push button *g* is depressed, a local circuit is established as follows: from the upper side 115 of battery *x* over the wire 33 through the primary *m* of the transformer *l*, wire 25, contact 24, switch *s*, wire 21, battery *y* in series, windings of the interrupter *h*', wire 22 and wire 35 through push button *g*, back 120 to the lower side of battery *x*. This local circuit with the two batteries in series produces a powerful pulsating current through the primary *m* of the transformer and this in turn induces an alternating current of the same frequency in the secondary *k*, which alternating current passes out to line over the wires 2 and 1 and receiver *r*.

125 When neither calling nor receiving telegraph messages the switch *s* may be swung 130

over into dotted line position so as to stop the operation of the interrupter and thus prevent wasting the local battery *y*.

It sometimes happens that, owing to the extreme sensitiveness of the apparatus, the proper reading of messages is interfered with by stray earth currents or the like. To obviate this difficulty, I provide means for balancing the stray E. M. F. by means of a potentiometer device. This consists of a coil *u* connected at one end to the wire *z* and at the other end by means of a wire 36 to a pair of contacts 37 and 38 of a reversing switch *w* which is in turn connected with a battery *v*. A second pair of contacts 40 and 41 are connected by means of a wire 39 with the wire *z*. The telephone receiver *i* and associated parts are connected by means of the wire 12 with the potentiometer slide 13 on which is adjustably mounted the contact 42. It will be seen that by means of the reversing switch *w* an electromotive force from the battery *v* can be impressed on the line *z* in either direction and that by means of the adjustable slide and contact arrangement the value of such electromotive force can be made to exactly balance that due to stray currents and thus noises in the receiver *i* absolutely prevented.

What I claim is:—

1. Telegraphic apparatus comprising an interrupter for breaking up the received signal current, a choke coil interposed between the interrupter and the line, a grounded conductor providing a shunt path to earth at a point between the interrupter and choke coil, and a condenser interposed in said conductor.
2. In a combined telegraph and telephone system, a receiving station having two telephone receivers, such receivers being connected permanently in series in the telegraphic signal circuit, an impedance coil and the secondary of a telephone transformer being also included in said circuit, and an interrupter device interposed in said circuit between the impedance coil and one of said telephone receivers.
3. In a combined telephone and telegraph system, the combination with the usual tele-

phone receiver, transmitter and transformer, of means for generating in the secondary of the transformer a strong alternating current for calling a distant station, 55 such means comprising a source of direct current and an interrupting device connected in series with the primary of said transformer.

4. In a combined telephone and telegraph system, the combination with the usual telephone receiver, transmitter and transformer, of an auxiliary telephone receiver, an electromagnetic interrupting device, means for connecting said device in circuit with a 60 source of direct current and the primary of said transformer in order to generate in the secondary of the transformer a strong alternating current for calling purposes, and means for causing said device to break 70 up incoming intermittent telegraphic code signal current into high frequency impulses audible in the auxiliary telephone receiver.

5. In a combined telephone and telegraph system, the combination with the 75 usual telephone set and transformer, of a second telephonic receiver, means for breaking up the usual intermittent code signals coming in over the line into high frequency impulses audible in such second 80 telephonic receiver, such means including an electromagnetic interrupter and a local battery for operating the same, a main battery for transmitting telegraphic signals and means for generating a strong alternating 85 calling current in the secondary of the said transformer, such means including said main and local batteries connected in series with the primary of said transformer.

6. In a telegraph system, the combination 90 with a telephonic receiver and means for rendering the usual code signals audible in such receiver, of means for preventing stray currents from entering said receiver, such means comprising a potentiometer device, 95 including a reversing switch and source of current, connected between the receiver and the external circuit.

In testimony whereof I have signed my name to this specification.

ALGERNON CLEMENT FULLER.
